CLAIM

The ornamental design for a paper bag with a horizontally spanning transparent window for salad ingredients, as shown and described.

DESCRIPTION

FIG. 1 is a perspective view of a paper bag with a horizontally spanning transparent window for salad ingredients showing our new design;

FIG. 2 is a front elevational view thereof;

FIG. 3 is a rear elevational view thereof; and,

FIG. 4 depicts the paper bag with a horizontally spanning transparent window for salad ingredients, with the new, original and ornamental design in a display.

The broken line showing of a shelf is included for the purpose of illustrating the bag in display and forms no part of the claimed design.

The stylized leaf pattern is a trademark of Fresh Express, Inc.
